VOIGT & HAEFFNER ACTIEN GESELLSCHAFT, OF FRANKFORT-ON-THE-MAIN, GER-
MANY.

ELECTRIC SWITCH.

1,417,957.

Specification of Letters Patent. Patented May 30, 1922.

Application filed June 5, 1915. Serial No. 32,370.

(GRANTED UNDER THE PROVISIONS OF THE ACT OF MARCH 3, 1921: 41 STAT. L. 1212.)

To all whom it may concern:

Be it known that I, MAX VOGELSANG, a subject of the German Emperor, and a resident of Frankfort-on-the-Main, Germany, ⁵⁵ have invented certain new and useful Improvements in Electric Switches, of which the following is a specification.

The present invention relates to improvements in electric switches and the object of ¹⁰ the improvements is to provide means for effectively releasing such switches after a certain time has lapsed.

In the case of a number of electric switches being placed in series in a network ¹⁵ it is desirable, whenever the network is over-loaded or short-circuited, to get the switch next to the point of short-circuit released. This is usually effected by making the time for releasing the switch dependent upon the ²⁰ drop of voltage at the point in question. In that case, owing to the fact that the drop of voltage will be greatest near the point of short-circuit, the switches nearest to said point, owing to the time lag relay being influenced by the drop of pressure, will be ²⁵ released earlier than the switches placed at some distance from said point. An arrangement of this sort is useful as well for ordinary branched networks as for closed ³⁰ systems. Its usefulness for these latter systems is the more apparent as owing to said arrangement the two switches nearest to the point of short-circuit and of the lowest voltage have the shortest time of release, the ³⁵ point in question being therefore cut out in the simplest manner without any branch circuits being employed.

The time lag relays heretofore used in connection with arrangements based on the ⁴⁰ principle mentioned above generally make use of the braking force of an electromagnet excited by the voltage to influence the time lag relay. Obviously this braking force will be the smaller, the greater the ⁴⁵ drop of voltage caused by the short-circuit, and the time lag relay will run down the quicker the greater the drop in voltage at the point in question.

The practical application of these time ⁵⁰ lag relays, however, is hindered by the circumstance that the braking effect requires comparatively great electric forces. It is further difficult to adjust at will the de-

vices operating according to the braking system for all voltages, from the full voltage down to zero. ⁵⁵

According to the present invention all these difficulties are surmounted by not depending upon the braking effect exerted by the voltage upon the time lag relay and simply using the holding power of an electromagnet excited by the voltage for counter-⁶⁰ acting the effect of an elastic force increasing, as the time proceeds. This arrangement may be applied to time lag relays in-⁶⁵ dependent of the passing current as well as to such relays as are influenced by this current, and it is possible to effect the release of the switch either directly by the holding magnet or indirectly by an auxiliary cur-⁷⁰ rent.

In the drawings affixed to this specification different forms of an arrangement according to the present invention are shown diagrammatically. ⁷⁵

In the arrangement shown in Fig. 1, 1 is a high tension maximum relay, 2 is a time lag relay excited whenever contact is made, thus causing core 3 to be slowly pulled into the coil 5 under the influence of the stopping device 4. When the contact is opened at 1, the core 3 will fall freely down, a ratchet being inserted in the mechanism. The core 3 of the time lag relay is connected by a spring 6 with the armature 7 of a magnet 8 excited by the voltage s in such a manner that the tension of the spring 6 in pulling the core 3 into the magnet 5 is gradually increased. As soon as the tension of the spring has overcome the holding ⁸⁰ power of the magnet 8, the armature is pulled off and the contact device 9 for the indirect release of the high tension switch 10 is closed. ⁸⁵

It is clear that the length of the period ⁹⁰ of time required for the pulling off of the armature 7 is dependent upon the excitation of the magnet 8 at that time. If the voltage is low and in consequence thereof the holding power of the magnet is small, ¹⁰⁰ the armature will be pulled off by a relatively low tension of the spring, that is to say, after a short time. On the other hand, if the excitation of the magnet is rather high, the time lag relay will pull the core ¹⁰⁵ 3 far into its coil and will have to apply a

strong tension to spring 6 before the attractive force of the magnet is overcome and the armature is pulled off.

A similar mode of operation results in an arrangement where the time lag relay is influenced by the intensity of the current. Referring to Fig. 2, 11 is a transformer exciting by magnet 12, the magnet trying to drive the Ferraris disc 13. This latter is held in its normal position by the action of spring 6, until the driving force of magnet 12 begins overcoming the tension of spring 6. The disc now starts rotating and gradually pulls spring 6 up, its speed being regulated by a braking magnet 14 or by a governor or the like. The effect exerted by this arrangement is the same as described above, save the well known difference between the dependent and independent time lag relays. Instead of having the armature 7 act upon a contact device 9, the release of the switch 10 may as well be effected directly, as shown for instance in Fig. 3, a suitable system of levers 15 being provided to this end. Obviously the excitation of the magnet requires only a very small amount of energy and the adjustment of the device will be accurate for a wide range of voltage, the pulling off of the armature 7 at a certain exciting voltage and a corresponding dimensioning of the magnet 8 always requiring a clearly defined tension or force of the spring 6.

It might however happen that in the network provided with an arrangement according to the present invention, instead of a direct short-circuit, only a high and lasting overloading takes place, thus keeping the

time lag relay 2, after the maximum relay 1 has been actuated, working during the whole time, the spring 6 being expanded to its maximum length without the armature 7 being pulled off and without switch 10 being released. It is necessary, in such a case, to have the switch released merely in consequence of the excess of intensity of current prevailing all through the time to which the relay has been adjusted, although the armature is not pulled off. To this end the time lag relay 2 may be caused, in such a case, after having nearly completed its movement to release the switch by mechanically influencing a pawl mechanism or the like adapted to close or open a contact.

In the arrangement shown in Fig. 4 an independent time lag relay is provided which causes the switch 10 to be released, as soon as the spring 6 has been fully expanded, by closing a special contact 16 for the releasing coil 17 of switch 10.

60

I claim:—

In a device of the class described, in combination, an electric switch, a time lag relay adapted to be influenced by a drop of voltage caused by overloading and to release said switch and means connected with said relay for releasing said switch also in case that no drop of voltage occurs, but the overload merely causes the time lag relay to run down.

70

In testimony whereof I affix my signature in presence of two witnesses.

MAX VOGELSANG.
